UNITED STATES PATENT OFFICE.

BENJAMIN SLUSSER, OF SIDNEY, OHIO.

IMPROVEMENT IN CAR-COUPINGS.

Specification forming part of Letters Patent No. **159,462**, dated February 2, 1875; application filed January 11, 1875.

To all whom it may concern:

Be it known that I, BENJAMIN SLUSSER, of Sidney, in the county of Shelby and State of Ohio, have invented a new and Improved Car-Coupling; and I do hereby declare that the following is a full, clear, and exact description of the same, reference being had to the accompanying drawing forming a part of this specification, in which—

Figure 1 is a front, and Fig. 2 a side, elevation.

The invention relates to novel means whereby cars may be conveniently coupled, securely held in connection, and easily uncoupled, all as hereinafter fully described, and subsequently claimed.

A A represent two draw-bars, each provided with a vertical stud, a, on the upper front end. B is a link, pivoted at b on top of each draw-bar, some distance in the rear of stud a, and provided with two lateral eyes, b' b', which receive loosely the end hooks, c c, of the bent rod C. D is a rock-shaft, which has central arm d, end arms, d' d', at an angle thereto, and the stops d² d², that work against the bearings E E, to limit the lateral play of said shaft. The arm d is bifurcated at the end, and has eyes, through which is inserted the rod C, that also passes through the end of a pivoted vertical rod, F. The latter also passes up obliquely through a loop or eye, G.

Between the arm d and the loop G is arranged a spiral spring, H, on the rod F. By raising an end arm, d', on either side of car, the shaft D throws the arm d over toward the car, and beyond the perpendicular plane, which passes through itself, whereby the spring is made to hold up the link. If, now, the reverse movement takes place at the contact of another car draw-bar, the link B is thrown over the latter's stud a, and firmly held by the spring, which presses the arm d on the forward side of said rod D.

This coupling is secure and reliable, the studs and all parts fast, and not subject to loss by accident or theft, while if one of the cars is switched off the track it becomes immediately detached.

If cars having draw-bars of unequal heights meet it is only necessary to use the lowest link, while the usual holes may be retained to admit of the use of pins.

Having thus described my invention, what I claim as new is—

The combination, with pivoted link B, of the bent rod C, shaft D, having arm d, vertical rod F, and spring H, as and for the purpose specified.

BENJAMIN SLUSSER.
